UNITED STATES PATENT OFFICE.

VANDIE D. CALDWELL, OF NATCHITOCHES, LOUISIANA.

MAIL CATCHING AND DELIVERING DEVICE.

1,244,582.

Specification of Letters Patent. Patented Oct. 30, 1917.

Application filed May 22, 1916. Serial No. 99,190.

To all whom it may concern:

Be it known that I, VANDIE D. CALDWELL, a citizen of the United States, residing at Natchitoches, in the parish of Natchitoches 5 and State of Louisiana, have invented certain new and useful Improvements in Mail Catching and Delivering Devices, of which the following is a specification.

This invention relates to mail bag catching and delivering devices, and has for its primary object to provide improved means for supporting or maintaining mail pouches adjacent a track and upon a car in such manner that the bags or pouches may be interchanged with as little jar or shock to the pouch or the supporting means as is possible, whereby breakage or tearing of the bags, or derangement of the supporting means is obviated.

20 A further object of the invention is to provide a device of this character wherein the delivery of the pouches either to or from the traveling car, or the stationary crane or support is positive, thus preventing loss of 25 the mail pouches during the catching operation.

A still further object of the invention is to provide the device of this character and for these purposes which is of exceedingly 30 simple and inexpensive construction, which is composed of but few readily assembled parts, all so constructed and arranged as to prevent wear, breakage, or derangement of the same, which is easy of operation, and 35 which will prove very efficient in the attainment of the ends for which it is designed.

With these objects in view, together with others which will appear as the description 40 proceeds, the invention resides in the novel formation, combination and arrangement of parts, all as will be described more fully hereinafter, illustrated in the drawings and specifically pointed out in the claims.

45 The invention will be best understood by reference to the accompanying drawings wherein;

Figure 1 is a view in elevation, and illustrating a mail pouch transferring apparatus 50 embodying the invention and in the act of delivering pouches from a moving car to the fixed catching or receiving device;

Fig. 2 is a plan view of the device;

Figs. 3 and 4 are enlarged detailed views 55 of the grip members;

Fig. 5 is a similar view of the pouch supporting hooks; and

Fig. 6 is a detail sectional view on an enlarged scale taken on line 6—6 of Fig. 1.

Referring now more particularly to the drawings, 7 indicates a crane standard or post, which is rotatably mounted in upstanding position within a suitable socket 8 embedded or in any other preferred manner secured to a suitable foundation such as a cement base 9. This post carries adjacent its lower ends a ratchet wheel 10, a pawl 11 being arranged upon the base to engage with the various ratchet teeth to limit the rotation of the wheel and post in one direction. This 70 post is braced by suitable struts 12, the latter being secured at their outermost ends to the base and being connected at their inner ends to a collar 13 fitting loosely around the post 7. An actuating arm or handle 14 is secured to the post to enable the latter to be readily rotated when required.

Secured to the post 7 and extending at right angles from the upper end thereof is a crane arm or support 15. This arm projects from a collar member 16 clamped upon the post by bolts 17, whereby the same is capable of being adjusted upon the said post. A second collar 18 is in a similar manner secured to the post 7 below the arm 15, and is connected to the rearwardly extending portion of the collar member 16 by a brace bar 19. This construction, while enabling the arm to be readily adjusted longitudinally of the post, affords a rigid support for the arm 90 to withstand the strain to which the latter will be subjected in the mail transferring or delivering operation. Depending from the arm 15 and in spaced relation to each other are grip members 20, the latter being constructed of spring metal, and providing at their lower ends spaced laterally projecting spring gripping jaws 21. The lowermost of the jaws 21 extends at substantially right angles to the body portion of the grip member and is beveled as at 22 upon its upper or gripping surface adjacent the outermost extremity of the jaw. The uppermost jaw projects laterally from a stem or arm held in spaced relation to the body portion of the grip member 20, and is spaced above the lowermost jaw and parallel to the beveled outer end thereof. This construction provides a relatively wide space between the juncture of the gripping jaws with their 100

105 grip member 20, and is spaced above the lowermost jaw and parallel to the beveled outer end thereof. This construction provides a relatively wide space between the juncture of the gripping jaws with their 110

supporting portions, and a contracted space at the extremities of the gripping jaws. The grip members are secured upon the crane arm 15 by means of bolts 23.

5 Arranged beneath the crane arm 15 and secured upon the post 7 in substantially the same manner as the crane arm 15, is a pouch receiving basket 24. This basket is supported through its upper rim or bail 25 by brace 10 members 26, the latter projecting from the sleeve 27 corresponding to the sleeve 18 for the crane arm 15. The body portion of the basket may be formed of heavy wire strands or rods of iron or other material, and are 15 preferably bowed or curved downwardly throughout the width of the basket and form a relatively shallow concave bottom therefor. This basket is relatively wide, and is 20 adapted to receive bags or pouches delivered from a passing train.

Pivoted supported as at 28 in the doorway of a railway car so as to swing outwardly therefrom, is a basket or collector arm 29, the latter supporting a basket 30 25 of heavy wire or iron bars, in such position as to lie and pass beneath the crane arm 15 projecting from beside the track. A hook 31 is secured to the car frame to support the basket in proper position projecting at right 30 angles to the direction of travel of the car.

Pivoted in a suitable bracket 32 upon the car door and directly beneath the arm 29, is a bag delivery arm 33. This arm is of such 35 length as to extend above and practically throughout the entire length of the basket 24 stationed beside the track, and is adapted to support mail pouches to be delivered to the said basket. This arm is equipped with spaced grip members 34 of substantially the 40 same construction as those described in connection with the crane arm 15. A hook 35 also maintains the bag delivery arm in proper projected position.

For use in transferring mail pouches from 45 the arms 15 and 33 to the baskets 24 and 30 beside the track and upon the car respectively, are pouch hooks 36. These hooks are formed preferably of iron or other metal bent at one end as at 37 to provide a hook 50 portion and being provided at their opposite extremities with openings 38, by means of which the said hooks are supported pendant from the grip members 20 and 34. The length of the hook members is such that 55 when supported at their apertured ends within the clamping jaws 21 of the grip members 20 and 34, the hook portions 37 at the lower ends thereof will be disposed in such position as to engage the arm 29 forming 60 the upper rim for the basket 30 upon the car, and the bail or rim member 25 supporting the basket 24 upon the crane post 7. The hooks 36 are arranged upon the crane 65 arm 15 so that their hook portions 37 project in the direction of approach of the train,

while those depending from the bag delivery arm 33 upon the car project in the direction of travel of the same. The jaw members 21 of the grips 20 and 34 project in opposite directions to which the hook 70 portions 37 extend, and it is apparent that as the train or car passes the crane beside the track, the bag supporting hooks pendant from the members 20 will be engaged at their hooked portions 37 by the arm 29 and 75 will be drawn from engagement between the spring jaws 21. The thickness of the upper portion of each of the members 36 is preferably such as will only permit of the member being withdrawn from or inserted between the jaws 21 when the said members are inclined. This inclination is delivered to the various hook members as they engage with the rim portions of the baskets 30 and 24 and as the train passes beyond the same. 80 It will thus be seen that the members 36 are thrown into the baskets as the car passes the crane beside the track. The mail bags or pouches are indicated at 39, and may be secured to the members 36 by straps 40, or 90 in any other preferred manner.

In operation, the bags are secured upon the hooks 36 and the latter adjusted to the grip members 20 upon the arm 15 through their openings 38. The crane post 7 is then 95 rotated within its bearing 8 until the arm 15 projects toward and at right angles to the direction of the track. The clerk within the car adjusts such of the bags as he wishes delivered to the particular station to the 100 delivery arm 33, and swings the latter, as well as the basket 30, into such position that they project from the car at right angles thereto. The hooks 31 and 35 are then connected to the basket and delivery arms to 105 maintain the same properly extended. As the car approaches the crane, the bags supported upon the hooks depending from the grip members 20 are caught in the basket 30, while those depending from the grip members 34 are delivered to the basket 24. The clerk may then swing the basket 30 to the interior of the car and readily remove the bags therefrom. The bags delivered to the basket 24 may also be readily removed there- 110 from. 115

It is thus seen that an extremely simple and yet thoroughly efficient means for transferring pouches from the car to the crane, and from the crane to the car, is provided. 120 It will also be observed that this method of transferring the pouches prevents breakage or tearing of the bags, and prevents the latter from dropping to the ground or being contacted by the wheels of the passing train. 125

While the above is a description of the preferred embodiment of the invention, it is obvious that various changes in the minor details of construction and arrangement of parts may be resorted to without departing 130

from the spirit of the invention or exceeding the scope of the claims.

What is claimed is:

1. In a device of the class described, a support, a grip member on said support, rearwardly extending spaced jaws on said grip member, a pouch carrying member comprising a bar having an opening in one end for engagement between said jaws, and the thicknesses of said bar being substantially equal to the distance between said jaws, substantially as described.
2. In a device of the class described, a post,

a pair of spaced collars on said post, a rod connecting said collars, means for adjusting said collars upon said post, a basket projecting outwardly from one of said collars, and braces connecting the extremity of said basket with the other of said collars, substantially as described.

In testimony whereof I affix my signature in presence of two witnesses.

VANDIE D. CALDWELL.
